Primary Examiner — Michael C Stout*Assistant Examiner* — Garrett J Armentor(74) *Attorney, Agent, or Firm* — Gugliotta & Gugliotta,
LPA(57) **CLAIM**

The ornamental design for a floor sign set as shown and described.

DESCRIPTION

FIG. 1 is a perspective top front right view of a floor sign set in a disassembled state, illustrating a base feature and a slider element feature, showing my new design;

FIG. 2 is a perspective top rear view thereof;

FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and,

FIG. 9 is an assembled view of the floor sign set in an assembled state, where the slider element feature is engaged with the base feature.
